CRIB SIDE LOCK

Herbert W. Neunherz, Gardner, Mass.

Application March 8, 1937, Serial No. 129,609

5 Claims. (Cl. 292—214)

This invention relates to a lock for general purposes and capable of holding the vertically movable side of a crib or similar article in its normal elevated position and for releasing the same. The principal objects of the invention are to provide a very simple device for this purpose; to provide a lock which will not readily be operated by accident to let the side drop; to provide a lock which is very easy to operate and will not readily get out of order, and to provide a construction for the above purposes in which a member is mounted to reciprocate or turn on the angle iron or the like which constitutes the front of the spring frame and a bracket, or the like, can be mounted on a crib side frame to be locked in its uppermost position and released therefrom.

Other objects and advantages of the invention will appear hereinafter.

Reference is to be had to the accompanying drawings, in which

Fig. 1 is a front elevation of a crib showing a preferred embodiment of this invention applied thereto;

Fig. 2 is a front view on enlarged scale of the locking mechanism;

Fig. 3 is a plan of the same;

Fig. 4 is a sectional view on the line 4—4 of Fig. 2 constituting an end view;

Fig. 5 is a sectional view on the line 5—5 of Fig. 2;

Fig. 6 is a front view on still further enlarged scale and showing the crib side locked in position;

Fig. 7 is a sectional view on the line 7—7 of Fig. 6;

Fig. 8 is a view similar to Fig. 7 showing the parts in unlocked position and the side frame drop;

Fig. 9 is a plan as indicated by the arrow 9 in Fig. 6;

Fig. 10 is a view similar to Fig. 2 of a modified form of the invention;

Fig. 11 is a plan of one end of the same;

Fig. 12 is a plan of the other end of the same;

Fig. 13 is an end view;

Fig. 14 is a sectional view on the line 14—14 of Fig. 10;

Fig. 15 is a view looking in the direction of the arrow 15 in Fig. 14;

Fig. 16 is a view of the locking mechanism like Fig. 14 except that the locking rod is turned to the unlocking position;

Fig. 17 is a view similar to Fig. 6 but showing another modification;

Fig. 18 is a sectional view on the line 18—18 of Fig. 17;

Fig. 19 is a sectional view on the line 19—19 of Fig. 17;

Fig. 20 is a view similar to Fig. 18 showing another modification, and

Fig. 21 is a plan of the bracket as indicated by the arrow 21 in Fig. 20.

This invention is shown as applied to a crib and that is the principal use for which it is intended. It can be applied to other beds and the like which have a side frame, normally held in elevated position and adapted to be dropped.

In the form shown in the first nine figures, the frame 10 of the crib supports a horizontal spring frame 11 of the usual type. This spring frame is provided with a bracket 12 and a bracket 13 on the front. Each of these is provided with a transverse plate 14 perforated to form a bearing for a pivot rod 15 which, in general, is cylindrical. At two points near the opposite ends it is provided with a flattened section 16 merely by slabbing off the opposite sides. This section, however, does not come at the bearings but beyond them. At one end this rod has fixed to it a two-pointed stop 17 adapted to bear on the bracket 13 at that end to limit the oscillating motion of the rod. The other end is provided with a fixed arm 18 which is connected by a link 19 with a lever 20 pivoted at 21 on a bracket 22 secured to the bottom of the angle iron which constitutes the frame 11. On the pivot 21 is mounted a spring 23 with one end held and the other end projecting forward and under the lever 20. Two of these levers, of course, are provided, only one of them with the link 19 and they support a trip bar 24 which normally is located just below the edge of the frame 11.

It will be seen that the springs 23 at the two ends of the frame, which is made up of the levers 20 and the bar 24, tend to hold these levers forward. When the child is to be placed in the crib the attendant presses against this bar 24 with the knee and pushes it backwardly which results in turning the rod 15 from the position shown in Fig. 7 to that shown in Fig. 8.

On the bottom of the crib side 27 are two brackets 25 projecting downwardly and inwardly. Each has a circular recess 26, or rather one which is a little more than a half circle, in which the circular part of the rod 15 fits. It is the slabbed section 16 of the rod which rests in this recess. Consequently when the rod 15 is turned to the position shown in Fig. 8 the vacant space at the top of the recess permits the brackets to

drop from the rod, as shown in Fig. 8. It is this turning of the rod 15 by the action just above described that permits the crib side or drop side 27 to drop. When it is returned the bar 24 has to be pushed back as described to bring the rod 15 to the position shown in Fig. 8. Then, when the crib side is pushed up and the bar released, the springs will return it to the position shown in Fig. 7, which is the locking position. The brackets 25 have diverging sides 28 from the tops of the recesses 26 to facilitate the raising of the crib side.

One of the brackets 25 has a projection 29 which, on its drop, engages the end of the stop 17 and turns this stop, as indicated by the arrow in Fig. 8, to let the projection pass by and to turn the rod 15. The springs 23 then turn the rod back by restoring the trip bar 24 to its normal position as shown in Fig. 7. Upon the lifting of the crib side 27, the same projection swings the stop back enough to allow the projection 29 to pass above the stop and to let the recess receive the rod 15. The springs 23 then restore the rod 15 to the position shown in Fig. 7 and the crib side is locked 25 in elevated position.

It will be seen, therefore, that the apparatus for locking the crib side in its highest position is extremely simple and inexpensive. Furthermore, if a dog or other domestic animal rubs against the trip bar 24 he is not likely to set it back so as to release the side, nor is it apt to be moved far enough for that purpose accidentally in any other way. The cost of manufacture and assembly is very small compared with any other device that 35 is at all safe that is on the market.

In the form shown in Figs. 10 to 16 inclusive the oscillating rod 30 may extend the whole length of the side of the spring frame 11 and is so shown. It is provided with the same kind of a stop 31 as 40 the one described in the other figures but shown of different shape. The rod is supported on two brackets 32 secured to the spring frame. It is also provided with two sections 33 of the same shape, preferably, as shown in Figs. 7 and 8. On 45 the one extreme end is wound a spring 34 secured at one end 35 to the bracket. The other end engages an arm 36 fixed to the rod 30 and normally holds the rod 30 in locking position. This arm 36 has eccentrically pivoted to it the end of an operating lever 37 which normally hangs down at one 50 end of the crib near the leg thereof where it is out of the way and where it is not likely to be tampered with by children or domestic animals. This rod can be folded back in the frame for shipping, as shown in Figs. 12 and 13.

The operation is the same as in the other case. Brackets 25^a on the crib side are held by the rod against dropping of the crib side. A projection 38 from one of these brackets operates the stop 31 in 60 a manner similar to that described with reference to the first nine figures. This action is shown clearly in Fig. 16. In this case the advantages are substantially the same as in the form illustrated.

The invention can be carried out by reciprocating the locking rod instead of oscillating it. This is shown in the two forms illustrated in Figs. 17 to 21. In Figs. 17 to 19 inclusive the locking rod 40 reciprocates to lock and unlock the crib side 27. In this instance, the rod is provided with two 70 sections 41 of reduced diameter, which may be concentric.

The crib side has two brackets 42 almost like the brackets 25. When the rod 40 is in a position in which the rod fills the recesses in these brackets, the crib side is locked. When it is moved lon-

gitudinally to a position, as shown in Fig. 18, in which the recesses receive the reduced sections 41 it is unlocked and the crib side is free to drop.

On the rod 40 is coiled a spring 43 located between a collar 44 on the rod and a guide 45 fixed 5 on the spring frame 11. Thus the spring constantly tends to push the rod to the right. Stops 46 and 47 are provided to limit the endwise motion of the rod.

On the rod is fixed a slanting cam 48 for cooperating with a similar, but opposite, cam 49 on the crib side. When the rod is moved to the left the cam 48 moves with it. The reduced section 41 moves into the position, shown in Fig. 18, and the crib side is freed. This is done by any kind of a 15 link motion, or the like, 50 working against the spring 43.

When the side drops the spring 43 moves the rod 40 back to the position shown in Fig. 17. When the crib side is raised, as shown in dotted 20 lines in Fig. 17, the cam 49 engages the slanting side of the cam 48 and pushes it and the rod to the left until the cam 49 passes above the cam 48.

In the form shown in Figs. 20 and 21 a locking bolt 51 moves transversely to the direction of 25 motion of the rod 40. It passes into a hole 52 in a bracket 53 on the crib side 27. This bolt is moved into locking position by a crank motion 54 against a spring 55. The bolt operates between two stops 56 and 57. The bolt has a reduced portion 30 58.

Having thus described my invention and the advantages thereof I do not wish to be limited to the details of construction herein disclosed, otherwise than as set forth in the claims, but what I 35 claim is:

1. The combination with a movable member and a stationary member, of a rod carried by the movable member having a portion thinner than the rest, a bracket on the movable member having a circular slot cut out at the top to provide a notch through which the thin portion of the rod can pass, whereby, when the rod is turned to such position as to register with the slot, the bracket has no support and will allow the movable member to move, a pivoted foot treadle connected with the rod for moving it into locking position, and a spring engaging the spring frame and the treadle to normally keep the rod in a position with the thinner portion horizontal to 50 lock the side frame in elevated position.

2. The combination of a bracket having an upwardly opening notch therein, with a slot at the top, the walls of the notch being nearer together at said slot than at a point slightly below it, a 55 rod oscillatably mounted and having a thinner portion adapted to enter the notch and hold up the crib side when turned into one position, two pivoted levers extending downwardly, a horizontal rod connected with the said levers, and means for turning the first named rod by the action of said lever, whereby the latter rod can be turned by manipulation of said levers into a position to allow the side frame to drop.

3. The combination of a stationary bracket having an upwardly opening notch therein, with a slot at the top, the walls of the notch being nearer together at said slot than at a point slightly below it, a rod oscillatably mounted and having a flattened portion located and adapted to enter the notch when turned away from vertical position, a pivoted lever extending downwardly, a link connected with said lever, and an eccentric on the rod pivoted to said link, whereby the rod 75

can be turned by manipulation of said lever to bring the flat portion into different positions.

4. The combination of an oscillatable rod having a portion thinner than the rest, a bracket having a circular slot cut out at the top to provide a notch through which the thin portion only of the rod can pass, whereby, when the rod is turned to such position as to register with the slot, the bracket has no support, a lever on the end of said rod, an arm pivotally connected with the lever and adapted to hang down from it for operating it, and a spring surrounding the rod engaging the spring frame on one end and the arm on the other to normally keep the rod in a position to lock the crib side in elevated position.
5. The combination with two members, one stationary and the other vertically reciprocable, located closely adjacent to each other, a bracket on the reciprocable member projecting toward the stationary member, said bracket having a substantially circular perforation and opposite

slanting surfaces projecting upwardly from said perforation in opposite directions symmetrically, brackets on the stationary member, a longitudinal shaft oscillatably carried by the two brackets, means for oscillating said shaft, said shaft having a flat portion of the full size of the shaft in its long dimension and thin enough in a direction at an angle to the long dimension to pass into the top of said perforation, the said slanting surfaces constituting means for guiding the shaft into said perforation, when the shaft is in a position with its flat portion vertical, a stop on the shaft for limiting its oscillation in one direction to a position in which the flat portion is horizontal to lock it in the perforation, and a stop on the shaft to limit its oscillation in the opposite direction to a position in which said flat portion is vertical to allow it to move into and out of said perforation.
